UNITED STATES PATENT OFFICE

112,320

DESIGN FOR A DRESS

Albert E. Levy, New York, N. Y.

Application October 29, 1938, Serial No. 80,737

Term of patent 3½ years

To all whom it may concern:

Be it known that I, Albert E. Levy, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

ALBERT E. LEVY.
